Primary Examiner — Samantha Wood(74) *Attorney, Agent, or Firm* — Birchwood IP(57) **CLAIM**

The ornamental design for an alarm clock, as shown and described.

DESCRIPTION

FIG. 1 is a front, left and top perspective view of an alarm clock, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of portion 9 encircled in FIG. 1; and,

FIG. 10 is an enlarged detail view of portion 10 encircled in FIG. 1.

The broken lines shown in the drawings illustrate portions of the alarm clock that form no part of the claimed design. The dot-dash broken lines depict the boundaries of the enlargements that form no part of the claimed design.

1 Claim, 10 Drawing Sheets(56)
